UNITED STATES PATENT OFFICE.

MERLIN E. CUSTER, OF CARBONADO, WASHINGTON.

AUTOMATIC STARTING-BOX.

1,103,662.

Specification of Letters Patent. Patented July 14, 1914.
Application filed February 26, 1913. Serial No. 759,766.

To all whom it may concern:

Be it known that I, MERLIN E. CUSTER, a citizen of the United States, and a resident of Carbonado, in the county of Pierce, and 5 State of Washington, have invented certain new and useful Improvements in Automatic Starting-Boxes, of which the following is a specification.

My invention relates to automatic starting 10 boxes of the kind used in connection with electric cars, or other electrically driven machinery, or with electric lamps for the purpose of first causing a small flow of current through the main or power circuit, and 15 then increasing the flow step by step until the current reaches its normal or working power.

More particularly stated, my invention 20 comprehends a number of branching circuits each including an individual resistance, these circuits being closed one at a time in a definite order of succession until the full measure of electric power is turned on, after 25 which all of the circuits except one are opened in a definite order of succession, the one remaining closed being always energized under normal working conditions, the means for opening and closing the circuits being automatically operated.

30 Reference is made to the accompanying drawings forming a part of this specification and in which like letters indicate like parts.

The figure is a view partly in front elevation and partly diagrammatic showing my 35 improved starting box with all of the resistance units, the various parts here appearing in their normal or idle positions.

Mounted upon the board 11 are a number 40 of solenoids 12, 13, 14, 15, and 16. The solenoids 12, 13, 14 and 15 are of any desired resistance and the solenoid 16 is of high resistance, suitable for avoiding undue waste of current with the voltage to be employed. 45 Mounted upon a base 17 is a magnet 18 also of high resistance, and adjacent to this magnet is an armature 19 which is provided with a contact 20. Binding posts are shown at 21, 22, 23 and 24. The base 17 and parts 50 mounted upon it together constitute a relay. Mounted upon a board 24^a is a magnet 25 adapted for series connection with the solenoid 16, and adjacent to this magnet is an armature lever 26. This lever is provided 55 with an extending portion 27 which acts to

some extent as a spring and carries at its outer or free end an eye 28.

A pin 29 is mounted upon the base 24^a and serves as a limiting stop for the armature lever 26. A contact 30, controllable by the 60 armature lever 26, is adapted to open and close a circuit, as hereinafter described. The binding post 31 is connected with one of the members of the contact 30. This binding post 31 is connected by a wire 32 with the 65 solenoid 16. Another binding post 33 is mounted upon the base 24^a and is connected with the magnet 25, this magnet being also connected with the binding post 31.

The base 24^a and parts carried by it together constitute a relay. A number of movable cores 34, 35, 36, 37, 38 are provided, each core serving as the armature of one of the solenoids 12, 13, 14, 15, 16. Each core slidably engages a bearing 39 and carries a disk 75 40 of semi-conducting material, having in this instance the form of a disk. The disks carried by the cores 34, 35, 36 and 37 are each of high resistance, while the disk carried by the core 38 is of comparatively low 80 resistance commensurate with the maximum current to be used in the power circuit.

Below each solenoid are located two holders 40^a, 41 carrying stationary contact members 42, 43 which may conveniently have the 85 form of carbon rods. Adjacent to the solenoids 12, 13, 14 and 16 are movable arms 44, 45, 46, 47, each carrying a contact member 48, 49, 50, 51, these contact members being severally engaged by the carbon disks 90 40 whenever the cores of the solenoids are drawn upwardly.

A transformer is shown at 52 and is provided with a primary winding 53 and a secondary winding 54. The secondary winding 95 is connected by wires 55, 56 with the work to be done by the current. A wire 57 is connected with the primary winding 53 and also with a power main 58. Connected with the main 58 is a wire 59 and extending 100 from this wire to the solenoid 16 is a wire 60. Connected with the wires 59, 60 is a wire 61 and extending from the latter to the solenoid 15 is a wire 62. The wires 61, 62 are connected to a wire 63 and from the latter a 105 wire 64 extends to the solenoid 14. The wires 63, 64, are connected to a wire 65, this wire being connected to another wire 66.

A wire 67 is connected to the wires 65, 66 and also to the solenoid 18. A wire 68 is 110

connected with the wire 66 and with the solenoid 12. A wire 69 is connected with the wires 66, 68 and leads downwardly to the binding post 21.

5 Connected with the binding post 23 is a wire 70 which extends upwardly and is connected with the solenoid 12. A wire 71 extends from the swinging arm 44 to the solenoid 13. Similarly a wire 72 extends from the arm 45 to the solenoid 14 and another wire 73 extends from the swinging arm 46 to the solenoid 15.

10 A wire 74 leads from the swinging arm 47 to the binding post 22. Connected with the binding post 24 is a wire 75 to which is connected a wire 76 leading to the binding post 33. A wire 77 is connected to both of the wires 75, 76 and with a main 78. A wire 79 is connected with this main and also 15 with a wire 80 which leads to the holder 41 below the solenoid 16.

15 A wire 81 is connected to the wires 79, 80 and also with a wire 82, the latter leading to the holder 41 below the solenoid 15. Connected with the wires 81, 82 is a wire 83 and connected with the latter is a wire 84 which leads to the holder 41 below the solenoid 14. The wires 83, 84 are connected to a wire 85. Connected with this wire is a wire 86 which 20 leads upwardly to the holder 41 below the solenoid 13. A wire 87 is connected to the wires 85, 86 and with the holder 41 below the solenoid 12.

25 Connected with the winding 53 of the transformer 52 is a wire 88 and leading upwardly from this wire is a wire 89 which is connected with the holder 40^a below the solenoid 12. Connected with the holder 40^a of the solenoid 13 is a wire 90 which leads 30 downwardly and is connected with a wire 91, this wire being also connected with the wires 88, 89. A wire 92 is connected with the wires 90, 91 and also with a wire 93 which leads upwardly to the holder 40^a below the solenoid 14.

35 A wire 94 is connected with the wires 92, 93 and also with a wire 95, the latter extending upwardly to the holder 40^a below the solenoid 15. Connected with the wires 94, 40 95 is a wire 96 which leads to the holder 40^a below the solenoid 16. Connected with the lower end of the core 37 is a rod 97 which is provided at its lower end with a knob 98, and also at a little distance above its lower 45 end with a collar 99. The portion of the rod 97 between the eyes 98, 99 extends loosely through the eye 28 so that the rod 97 can have a measured amount of vertical play without moving the lever 26, but after moving a predetermined distance will cause the lever 26 to move.

50 While in this instance I disclose the use of the transformer 52, it will be understood that this transformer is not essential, though 55 desirable if alternating currents are used;

and that the wires 57, 88 may be connected directly with a number of resistances, or with the motor or machine to which current is to be supplied. This is always the case in instances where direct current is to be used.

50 The operation of my improved device is as follows: I will first assume that the device is idle and that the mains 58, 78 are disengaged from the source of power. The weight of the various cores 34, 35, 36, 37, 38 maintains these cores in their lowermost respective positions, as indicated in Fig. 1. The armature 19 and the armature lever 26 are also in their lowestmost positions, the contact 20 being closed and the contact 30 being open. Suppose now that the mains 58, 78 are energized or closed so that the power is turned on. The following circuit may now be traced: source of power, (not shown) main 78, wire 77, binding post 24, armature 85 19, contact 20 (now closed), binding post 23, wire 70, solenoid 12, wires 68, 66, 65, 63, 61, 59 and main 58 back to source of supply. This energizes the solenoid 12 so that the core 34 is raised to its upper limit, the disk 40 being thus brought into engagement with the contact members 42, 43 and 48. Another circuit is thus completed as follows: source of power, main 78, wires 79, 81, 83, 85, 47, holder 41, contact member 43, carbon 95 disk 40, contact member 48, arm 44, wire 71, solenoid 13, wires 67, 65, 63, 61, 59, main 58 back to source of supply. This energizes the solenoid 13 and causes it to lift its core 35 90 so that the disk 40 carried by this core is brought into engagement with the corresponding contact members 42, 43 and 49 associated with the solenoid 13. Another circuit is thus completed as follows: source of supply, main 78, wires 79, 81, 83, 85, 86, 100 105 contact member 43 below solenoid 13, carbon disk 40 carried by core 35, contact member 49, arm 45, wire 72, solenoid 14, and wires 64, 63, 61, 59 and main 58 back to source of supply. This energizes the solenoid 14 and causes it to lift its core 36 110 115 as above described with reference to the lifting of the core 35 by the solenoid 13. Another circuit is thus completed as follows: source of supply, main 78, wires 79, 81, 83, 84 to the contact member 43 adjacent to the core 36, disk 40, contact member 50, wire 73, solenoid 15, wires 62, 61 and 59, to main 58 and thence back to source of supply. This energizes the solenoid 15 and causes it to 120 lift its core 37. This raises the rod 97 and in so doing causes the knob 98 to engage the eye 28 and thus swing the armature lever 26 upwardly so as to close the contact 30. This completes the following circuit: source of 125 supply, main 78, wires 77, 76, magnet 25, binding post 31, wire 32, solenoid 16, wires 60 and 59 and main 58, back to source of supply. This circuit energizes both the magnet 25 and the solenoid 16 so that the contact 30 130

is now maintained closed independently of the lifting action of the rod 97, in other words is held up by attraction of the magnet 25.

5 As will be seen from the foregoing description, the solenoids 12, 13, 14, 15 and 16 are energized in rapid succession and as each solenoid is energized it actuates mechanism for completing a circuit through the 10 next successive solenoid until all of the solenoids are in action at the same time. As the solenoid 12 is energized at the beginning of the operation the parts appear as indicated in Fig. 2, and Figs. 3, 4, 5 and 6 indicate the various positions occupied by the 15 several movable parts as the other solenoids 13, 14, 15, 16 are successively energized. Each of the solenoids as it becomes energized also completes a branching circuit affecting the transformer 52. As the solenoid 12 is energized so as to raise its core 34 into its uppermost position, as above described, the following circuit is completed: 20 source of supply, main 78, wires 79, 81, 83, and 87, contact member 43 below solenoid 12, adjacent contact disk 40, and contact member 42, holder 40^a, wires 89, 88, primary winding 53, wire 57 and main 58, back to source of supply. This 25 energizes the primary winding 53 to an extent dependent upon the ohmic resistance of the carbon disk 40 carried by the core 34. As the solenoid 13 is energized, as above described, so that the core 35 is lifted and 30 the contact disk 40 carried by this core is brought into engagement with the contact members 42, 43, and 49 above it, the following circuit is completed: source of supply, main 78, wires 79, 81, 83, 85 86, holder 41, contact member 43 below solenoid 13, adjacent contact disk 40, contact member 42, holder 40^a, wires 90, 91, and 88 to primary winding 83, thence through wire 57 and main 58 back to source of supply. It will 35 be noted that the primary winding 53 is now energized by such current as can pass through two disks 40, which are in parallel with each other with reference to the primary winding. Similarly when the solenoid 40 40 is energized so that its core 36 is lifted into its uppermost position, another circuit similar to the two last described is closed through the next disk 40, so that the three consecutive disks 40 are now in circuit with the transformer winding 53 and are in parallel with this winding reference to the source of electrical supply, as may readily be understood from Fig. 4. As the solenoid 45 15 is energized and lifts its core 37, as indicated in Fig. 5, a circuit analogous to the three last traced is completed through the solenoid 15 and the winding 53 of the transformer, there now being four disks 40 in parallel with each other with reference to the primary winding of the trans-

former. As the solenoid 16 is energized and lifts its core 38, as indicated in Fig. 6, a circuit is completed through another disk 40 and the transformer winding 53 so that all of the five disks 40 are now in parallel with each other, and serve as so many resistance units for protecting the transformer. This condition of the parts, however, remains but a moment. The lifting of the core 38 of the solenoid 16 by bringing the contact disk 40 carried by its core into engagement with the adjacent contact member 51 completes the following circuit: 70 source of supply, main 78, wires 79, 80, adjacent holder 41, contact member 43, contact disk 40, contact member 51, arm 47, wire 74, binding post 22, magnet 18, binding post 21, and wires 69, 66, 65, 63 61, 59 and main 58 back to source of supply. This 75 energizes the magnet 18 and by causing it to attract its armature 19 causes the contact 20 to be opened. This accomplished, no circuit can now be traced through the solenoid 12 and this solenoid being thus de-energized no longer supports its core 34, 80 which thereupon drops into its lowermost position. Hence the disk 40 carried by the core 34 becomes disengaged from the contact member 43 and in so doing opens the circuit through the solenoid 13. The latter, in like manner, becoming now de-energized drops its core 35 and thus opens the circuit through the solenoid 14. This solenoid in turn, by becoming de-energized, causes the circuit through the solenoid 15 to be opened. 85 As the core 37 thereupon drops into its lowermost position, it no longer supports the armature lever 26, but as above described this armature lever is maintained in its uppermost position by the attraction of the 90 magnet 25 so that the contact 30 still remains closed. The solenoids 12, 13, 14, 15 being thus successively de-energized, as indicated in Figs. 7, 8, 9 and 10, no longer have any influence upon the supply of current through the primary winding 15, but a controlling circuit may now be traced as follows: source of supply, main 78, wire 79, wire 80 to holder 41, adjacent to core 38, contact member 43, disk 40, contact member 51, arm 47, wire 74, binding post 22, magnet 18, binding post 21, wires 69, 66, 65, 63, 61, and 59, and main 58 back to source of supply. This circuit by maintaining the contact 20 open prevents the solenoid 12 95 from being energized, and in doing this prevents any of the solenoids 13, 14, 15 from becoming energized. The power circuit, which is of low resistance and comparatively simple, may now be traced as follows: source of supply, main 78, wires 79, 80, holder 41, contact member 43, carbon disk 40, contact member 42, holder 40^a and wires 96, 94, 92, 91 and 88 to primary winding 53, thence through wire 57 and main 58 100 105 110 115 120 125 130

back to source of supply. The solenoid 16 and the magnet 25 are in series with each other, and remain energized while the power circuit is active. Since however, the solenoid 16 and magnet 25 are wound to a resistance suitable for the voltage employed in the power circuit, the loss of power from maintaining them energized constantly becomes negligible.

With the apparatus in the condition just described, namely, with the solenoid 16 and the magnet 25 energized and all of the other parts occupying their respective normal positions, as indicated in Fig. 10, the device may be used indefinitely, or so long as it is desirable to keep the transformer 52 energized, or to apply the current controlled by the device to any set of resistances or directly to the work to be accomplished. As soon, however, as power is cut off through the mains 58, 79 the solenoid 16 and the magnet 25 are deenergized so that the armature lever 26 drops into its lowermost position and rests upon the limiting stop 29. The drop of the core 38, by causing the contact disk 40 carried by it to disengage the contact member 51, now opens the circuit through the magnet 18 and causes the armature 19 of this magnet to drop and close the contact 20. This leaves the various movable parts in their respective idle positions, as indicated in Fig. 1. By closing the circuit through the mains 58, 79 the entire cycle of operations may be repeated.

I do not limit my apparatus to use in connection with currents of any particular kind, nor do I limit myself to the precise mechanism shown, the scope of my invention being commensurate with my claims.

Having now described my invention what I claim as new and desire to secure by Letters Patent is as follows:

1. In an automatic starting box, the combination of a plurality of solenoids, a movable core for each solenoid, a resistance unit connected with each core and adapted to be

thrown into and out of circuit by movements thereof, said resistance units being in parallel with each other with reference to the current supplied to the work, a circuit for energizing one of said solenoids, a contact for opening and closing said circuit, a magnet provided with an armature lever for actuating said contact, a connection from said armature lever to the core of one of the solenoids so that the movement of said last-mentioned core of one solenoid closes a circuit through said magnet and through another of said solenoids, and a contact controllable by said magnet and included in said last-mentioned circuit.

2. In an automatic starting box, the combination of a plurality of solenoids, a movable core for each solenoid, a resistance unit connected with each core and adapted to be thrown into and out of circuit by movements thereof, said resistance units being in parallel with each other with reference to the current supplied to the work, a circuit for energizing one of said solenoids, a magnet provided with an armature lever for actuating said contact, a connection from said armature lever to the core of one of the solenoids so that the movement of said last-mentioned core of one solenoid closes a circuit through said magnet and through another of said solenoids, a contact controllable by said magnet and included in said last-mentioned circuit, a second magnet, a circuit connected with said second magnet for energizing the same, contact mechanism controllable by the last of said solenoids to be energized for operating said circuit through said second magnet, and a contact controllable by said second magnet and included in the circuit of the first solenoid to be energized.
